1,425,769.

Specification of Letters Patent. Patented Aug. 15, 1922.

Application filed September 14, 1920. Serial No. 410,275.

To all whom it may concern:

Be it known that we, JOHN ARTHUR HIRST, and PERCY SMITH BROOK, subjects of the King of Great Britain, residing in the city and county of Chester, England, having invented certain new and useful Improvements in and Relating to Switches, of which the following is a specification.

This invention relates to rotary switches actuated by a step-by-step movement imparted by an oscillating handle which also by a secondary movement actuates an auxiliary switch, such for example as are described in the U. S. application filed by us on the 17th day of September, 1920, Serial No. 410,976, and the object is to improve and simplify the said mechanism and locking means so as to render the operation of the switch and the locking thereof more certain.

According to the present invention the handle controlled mechanism is enclosed in a two-part casing the one part of which is fixed and the other part of which (referred to as the handle part) is angularly movable; the two parts are provided with integral segmental flanges, and the one has a detachable segmental flange; these flanges retain the parts in proper axial position and permit relative angular movement between them, and are so arranged that the engaging flanges of the one part pass through the segmental spaces between the flanges of the other part and are held in place by the removable segmental part. The handle part, when the "full on" position is reached, is by the instrumentality of an axially movable locking piece carried by and axially movable with the auxiliary switch spindle and rotating with the main ratchet, locked against further movement, until the handle is released, and by its movement, relatively to the handle part (preferably in an axial plane normal to its spindle), causes the cam of the said spindle to move the locking piece axially out of engagement with a detent or detent locking lever. Damage to the switch by the too sudden operation of the handle is prevented by loading the handle pawl so that on any attempt to move it too quickly it is, by the action of centrifugal force, moved out of engagement with its ratchet. The overrunning of the device at the end of each stroke is prevented by a reversely set ratchet, the pawl of which is carried from the fixed part of the handle casing and is

caused to engage with its ratchet at the end of each forward stroke.

The invention is illustrated in the accompanying drawings in which:

Figs 1 to 3 illustrate the arrangement in which:—the handle has a semi-circular part embracing the casing; a reversely set ratchet is fitted to prevent over-running; and the locking is effected by engagement with the pawl of the reversely set ratchet.

Fig. 1 is a side elevation partly in section on a longitudinal plane I, I of Fig. 2.

Fig. 2 is an elevation partly in section on a transverse plane II, II of Fig. 1.

Fig. 3 is an outside elevation viewed from the handle part end.

Fig. 4 is a view similar to Fig. 1 but shows the arrangement when the cam spindle is a prolongation of the handle axis.

Figs. 5 to 8 show the arrangement when the locking is effected by engagement with the main ratchet.

Fig. 5 is a side elevation partly in section on the longitudinal plane V, V, of Fig. 6.

Fig. 6 is an elevation partly in section on the transverse plane VI, VI, of Fig. 5.

Fig. 7 is a view similar to Fig. 6, but shows the locking parts in engagement.

Fig. 8 is an outside elevation viewed from the handle part end.

Referring first to Figs. 1 to 3:—

A is the fixed part and B the movable part of the handle casing; C is the switch operating spindle or sleeve and c¹ is the clutch carried thereby which is adapted to engage a corresponding clutch on the main switch spindle; D is the auxiliary switch operating spindle, the insulated end d¹ of which engages with an axially disposed and movable rod which operates the auxiliary spindle (not shown).

H is the handle having, in this modification, a semi-circular extension carrying end bosses h¹ which are fixed to the protruding ends of a spindle h² mounted in the bosses b⁸ formed in the movable part B of the casing; this spindle h² carries a cam h³ which imparts axial movement to the auxiliary switch spindle D and the parts attached thereto.

The part A of the handle casing is provided with segmental flanges a¹ and the part B with segmental flanges b¹, and the part B is introduced into position in the part A by introducing the flanges b¹ through the

segmental spaces between the flanges a^1 ; by turning the part B, these flanges a^1 , b^1 , and the flange b^2 on B interlock axially, and they are retained in position by the insertion, 5 in one of the segmental gaps in the fixed part A of the detachable flange piece a^2 .

The main ratchet c^2 , the reversely set ratchet c^3 , and the indicator or shutter c^4 are fixed to the main switch operating 10 spindle C and rotate with it, and the locking piece d^2 is mounted on the auxiliary switch spindle D but it is caused to rotate with the spindle C and the main ratchets and reversely set ratchets by means of a pin d^3 15 which permits it to move axially in relation to these parts.

The main ratchet c^2 is operated by a pawl b^3 pivoted on a pin b^5 carried from the boss b^4 of the handle part B of the casing, and 20 the reverse ratchet c^3 is adapted at the end of each forward stroke of the handle part B to engage with a detent a^3 carried by a pin from the boss a^4 on the detachable segmental piece a^2 attached, by screws, to the 25 fixed part A of the casing. The detent a^3 has fixed to it and moving with it a locking lever a^5 , and a pin b^6 carried by the lug b^7 on the handle part B engages with the outer surface of the locking lever a^5 and 30 presses it and the detent a^3 inwardly against the action of a spring 5^a on the pivot pin of the detent a^3 and lever a^5 , so that at the end of each said stroke the forward movement of the reversely set ratchet c^3 is arrested by the detent a^3 . When the handle 35 part makes its return stroke the pin b^6 disengages from the locking lever and the spring of the detent a^3 turns it clear of the reverse ratchet c^3 and so permits the next 40 forward stroke to be made.

When the gear has been turned to the "full on" position, the locking piece d^2 will have been turned into that angular position in which its hook-shaped nose will engage 45 with the end of the locking lever a^5 when the latter has been pressed down by the pin b^6 into engagement with the reverse ratchet c^3 ; the gear will thus be positively locked against further movement until the handle 50 H is released, when it will be turned down through 180° in the direction of the arrow by a coil spring h^5 on the handle spindle h^2 , and will rotate the cam h^3 and so permit a coil spring on the switch rod in line with the 55 spindle D to move the latter axially; this axial movement displaces the locking piece d^2 from engagement with the locking lever a^5 , whereupon the spring of the latter turns it and the detent a^3 into the position shown 60 in Fig. 2.

Should it be desired to move the switch gear into its off position the handle H is grasped and returned to the position shown in Fig. 1 whereupon the cam moves the 65 spindle D and locking piece d^2 which moves

clear of the locking lever in its retracted position (see Fig. 2). The gear can now be turned by the to-and-fro movement of the handle to its off position from which, when it is desired to operate the gear again it 70 can be turned step-by-step to its full on position where it is again arrested as described. The full on and the off positions are indicated by indicator or shutter c^4 on which these words are printed and come opposite 75 a glazed window a^8 on the part A.

The cam h^3 is fixed on the spindle h^2 and held in axial position by the sleeve h^4 (see dotted lines Fig. 3). As the angular movement of this is 180° the full portion of it 80 may be made to embrace a considerable angle; any small oscillation of the handle H about its spindle h^2 does not therefore move the spindle D or the parts connected to it.

The main pawl b^3 may be weighted by 85 having a weight b^{10} cast on the end of it as shown by dotted lines Fig. 2, which weight will, by centrifugal force be moved outwardly if the handle be moved too suddenly.

The fixed part A of the handle part is attached to say, the main switch gear case by bolts passing through the lugs a^7 ; and the movable part has an end inspection cover b^9 .

Referring now to Fig. 4:—

In this modification the parts are, with the exception of the handle H' constructed as described. The handle spindle $h^{2'}$ is now made as a prolongation of the handle and is mounted in bosses h^6 ; the cam $h^{3'}$ is as before mounted on the handle spindle and the latter is controlled by a spring h^5' . The action is the same as that described, except that in order to operate the gear the handle H, when grasped by the hand, has to be 105 twisted about its axis in opposition to the spring.

Referring now to Figs. 5 to 8:—

The construction of the fixed and moving or handle parts A' and B' of the casing, the handle H', flanges $a^{1'}$ and $b^{1'}$, the flange $b^{2'}$, the spindle $h^{2'}$, cam $h^{3'}$, spindles C' and D' are substantially similar to the corresponding parts described in connection with Figs. 1 to 3. In the arrangement of Figs. 5 to 8, 110 which is the preferred one, the locking of the gear when the full on position has been reached is effected by locking the main pawl $b^{3'}$. The modification of construction is as follows:—

The reversely set ratchet and its detent and the operating pin for the latter may be fitted as described to prevent over-running, but they are omitted from Figs. 5 to 8; the main ratchet $c^{2'}$ and the shutter $c^{4'}$ are mounted on the main switch spindle C' as before and the main pawl $b^{3'}$ is pivotally carried by the pin b^{11} fixed to the part B' of the casing; the pawl $b^{3'}$ has fixed to it a transverse pin b^{12} , and a^8 is a locking lever carried on 125

a pin a^9 from the detachable flange piece a^2 which fits in the segmental space between the segmental flanges a^1 and holds the parts A' and B' from separating axially (when the 5 segmental flanges of the one part come opposite the segmental spaces of the other). The locking lever a^8 is adapted when turned into the position shown in Fig. 7 into which position it is turned when the gear is in its 10 full on position to engage the pin b^{12} on the pawl b^3 and hold the latter and the handle part B' fixed, but it is controlled by a spring a^{10} which normally maintains it against the limit stop a^{11} in the position shown in Fig. 15 6 in which it leaves the pin b^{12} free.

The locking piece d^2 which as before is mounted on the spindle D' and caused to turn with this spindle and the main ratchet by means of a pin d^3 sliding in a hole in the 20 ratchet c^2 ; when the gear reaches its full on position the locking piece d^2 engages the locking lever a^8 (see Fig. 6) and turns into and holds it in the position shown in Fig. 7 in which it engages the pin b^{12} on the 25 pawl b^3 and locks the gear.

When the handle is released and is turned by its spring through 180° the cam releases the spindle D', which as described then moves axially outward and carries the locking piece d^2 with it, this frees the locking lever which is then turned by its spring into the position shown in Fig. 6 in which position as will be seen by comparing the position of the locking lever in Fig. 6 and the 30 locking piece in Fig. 7 it is clear of the locking piece which can be moved axially back again as soon as the handle H' is turned up.

In other respects the construction and action is similar to that described in connection with Figs. 1 to 3.

The details of construction may be varied, for instance the two parts A' and B' to which the respective parts are attached need 45 not necessarily be made in the form of casings though this construction has the advantage of compactness and encloses the parts effectively.

The handle gear may be applied to any 50 form of switch gear, which is operated step-by-step by a to-and-fro movement; and though it is particularly applicable to cases where an auxiliary switch operated as described forms part of the gear it may, by 55 fitting a plain spindle D' instead of a switch operating spindle be used for switches without an auxiliary switch which needs to be operated by the transverse movement of the handle.

60 Having now fully described our invention we declare that what we claim and desire to secure by Letters Patent is:—

1. An electric switch operating mechanism comprising a handle member mounted 65 to be capable of movement in two directions,

switch operating connections whereby a step by step movement of said handle in one of said directions operates a switch member from off to on positions and vice versa, switch operating connections whereby movement of said handle in the other of said directions operates another switch member, automatic switch locking means arranged to be brought into action when said handle has completed its full on movement in said first 70 named direction, and means operated by the movement of the handle in said second direction for unlocking said switch locking means.

2. In an electric switch operating device, 80 a reciprocating switch operating member, a rotary switch operating member mounted to have a step by step rotary movement about said reciprocating member, an operating member mounted to oscillate about the axis 85 of said rotary member and also to have movement in a plane coincident with said axis, means whereby the movement of said handle in said first named direction operates said rotary switch member, means whereby 90 movement of the handle in the plane of said axis operates the reciprocating switch member, means for automatically locking said operating member when moved to full on position, and means operated by movement 95 of the handle in the plane of said axis for unlocking said locking means.

3. In an electric switch operating device; a reciprocating switch operating member, a rotary switch operating member mounted to have a step by step rotary movement about said reciprocating member, a transverse rock shaft having connections for operating said rotary member, a handle connected to said rock shaft and capable of pivotal movement about the axis thereof, a cam carried by said rock shaft arranged to actuate said reciprocating member, means for locking said rotary member on reaching full on position, and means actuated by said cam for unlocking said locking means.

4. In an electric switch operating device, 110 a reciprocating switch operating member, a rotary switch operating member, rotatable about said reciprocating member as an axis, a handle member movable in a plane perpendicular to said axis and also in the plane of said axis, pawl and ratchet means whereby movement of the handle in said first named plane imparts a step by step movement to said rotary switch operating member, means whereby movement of the handle in the plane of the axis moves said reciprocating switch operating member, means for automatically locking said pawl and ratchet mechanism on "full on" position of said rotary member, and means whereby movement of said handle in said axial plane unlocks said locking means.

5. In an electric switch operating device a rotary switch operating spindle, an axially movable switch operating shaft, an operating handle capable of movement in two directions, means whereby movement of said handle in one direction operates said spindle, said means including a ratchet on the spindle and pawl mechanism cooperating therewith, means whereby movement of said handle in the other direction operates said shaft, a locking member mounted on said shaft and rotating with the ratchet, a locking pawl arranged to be operated by said locking member to engage the ratchet when full on position is reached, and means whereby movement of said handle in said other direction imparts axial movement to said locking member to release said locking pawl.
6. In an electric switch operating device a rotary switch operating spindle, an axially movable switch operating shaft, a transverse shaft journaled in bearings which are revolvable about the axis of said spindle, a handle having a yoke connected to said shaft, means whereby the revolution of said bearings about said axis operates said rotary switch operating member, and a cam on said shaft arranged to operate said rotary switch operating member.
7. In an electric switch operating device a rotary switch operating spindle, an axially movable switch operating shaft, a stationary casing part, a second casing part rotatably connected therewith, means whereby the rotary movement of said second part operates said spindle, a handle for operating said rotary casing part, said handle being capable of movement in one direction relative to said second part, and means whereby movement of the handle in said direction operates said axially movable shaft.
8. In an electric switch operating device a rotary tubular switch operating spindle, an axially movable switch operating shaft
- within said spindle, a stationary casing part 45 in which said spindle is rotatably mounted, a removable casing part forming with said first named casing part a closure, said casing part having segmental engaging tongue and groove portions forming a detachable connection, a detachable member for holding said tongue and groove portions against accidental displacement, means whereby rotary movement of said removable casing part operates said spindle, and means for 55 axially moving said shaft.
9. In an electric switch operating device a rotatable switch operating spindle, an auxiliary switch shaft concentrically mounted in and axially movable relatively to the said 60 spindle, a spring controlled transverse shaft mounted so as to be angularly movable about the axis of the said spindle, having a fork, a handle attached to said shaft, a cam on said transverse shaft arranged to actuate the 65 auxiliary shaft, a ratchet on the said spindle, pawl coacting with said ratchet and operatively connected with said transverse shaft, a locking piece carried by the said auxiliary shaft and rotated by the said spindle and a 70 locking lever adapted to be moved into a position in which it locks the said pawl and ratchet, and which releases the said locking lever when it is moved axially when the handle is released and turns about the axis 75 of the said transverse shaft.
